UNITED STATES PATENT OFFICE.

CECIL H. DUCKETT AND CHARLES J. FITZPATRICK, OF WASHINGTON, DISTRICT OF COLUMBIA.

INNER TUBE.

1,267,063.

Specification of Letters Patent. Patented May 21, 1918.

Application filed September 15, 1917. Serial No. 191,600.

To all whom it may concern:

Be it known that we, CECIL H. DUCKETT and CHARLES J. FITZPATRICK, citizens of the United States, residing at Washington, in the District of Columbia, have invented certain new and useful Improvements in Inner Tubes, of which the following is a specification, reference being had to the accompanying drawings.

10 This invention relates to certain improvements in inner tubes for inflatable bodies and has relation more particularly to a device of this general character especially designed and adapted for use in connection with tires for automobiles or other vehicles, and it is an object of the invention to provide an inner tube with novel and improved means whereby puncture thereof, either by wear or from a medium exterior of the tire, 20 is substantially entirely eliminated.

It is also an object of the invention to provide a novel and improved inner tube wherein in the tread portion of the tube is provided with means for holding the tread portion 25 of said tube against expansion in a lateral, circumferential, or transverse direction so that the tread portion of the tube proper is held, when the tube is inflated, in substantially the same state as when the tube is deflated.

A still further object of the invention is to provide an inner tube with novel and improved means disposed circumferentially of the tread portion of the tube for maintaining said tread portion of the tube spaced or 35 separated from the inner wall of the tread portion of a casing or carcass in which the tube may be applied and wherein said means serves to relieve the tread portion of the tube proper against wear and further reduces to a minimum the possibility of puncture of the tube by a member which may penetrate the casing or carcass.

Furthermore, it is an object of the invention to provide a novel and improved inner tube having its tread portion provided with protuberances disposed circumferentially of the tube and which are adapted to maintain the tread portion of the tube separated from 50 the corresponding portion of a casing or carcass when the tube is applied therein and inflated and which also serves to protect the tread portion of the tube against wear and wherein said protuberances are arranged 55 within an inbow or depressed portion dis-

posed circumferentially of the tube so that the tube will properly fit within a casing or carcass with the possibility of pinching of the casing substantially eliminated.

The invention consists in the details of 60 construction and in the combination and arrangement of the several parts of our improved inner tube wherein certain important advantages are attained and the device rendered simpler, less expensive and otherwise 65 more convenient and advantageous for use, as will be hereinafter more fully set forth.

The novel features of our invention will hereinafter be definitely claimed.

In order that our invention may be the 70 better understood we will now proceed to describe the same with reference to the accompanying drawings wherein:

Figure 1 is a fragmentary view in top plan of a tread portion of our improved 75 inner tube, the same being in a flattened form; and

Fig. 2 is a transverse sectional view illustrating our improved inner tube arranged 80 within a casing or carcass.

As disclosed in the accompanying drawings C denotes a casing or carcass of any ordinary or preferred type and in which is adapted to be inserted our improved inner tube T.

The tube T is made of live rubber or other expandable material impervious to air and is molded or otherwise formed to snugly fit within the casing or carcass C when inflated.

The tread portion of the tube T is formed 90 with a circumferentially disposed annular depression or inbow 1 of a predetermined transverse width.

At substantially its transverse center the 95 depressed portion or inbow 1 is provided with the circumferentially disposed continuous annular outstanding rib or flange 2 formed of the same material as the tube T and preferably molded integrally therewith and which flange or rib serves effectually to prevent circumferential expansion of the tread portion of the tube T. Disposed diagonally of the tread portion of the tube T and entirely across the depressed portion or inbow 1 are the diagonally directed outstanding flanges or ribs 3 also formed of the same material as the tube T and integrally molded therewith. The ribs 3 are arranged in parallelism and are arranged 105 in predetermined circumferentially spaced 110

relation entirely around the tread portion of the tube T and are equi-distantly spaced. Also disposed diagonally across the tread portion of the tube T and entirely across 5 the depressed portion or inbow 1 are the ribs or flanges 4 of the same material as the tube T and integrally molded therewith. The ribs 4 are also in parallelism and disposed in circumferentially spaced relation 10 entirely around the tube T and equi-distantly spaced one from the other and also spaced apart substantially the same as the space between the ribs or flanges 3. The flanges or ribs 4 extend in a direction reverse 15 to the flanges or ribs 3 and preferably at the same angle relative to the rib 2 as the ribs 3.

The intersecting portions of the ribs 2, 3 and 4 are integrally connected and it is to be 20 understood that the ribs 3 and 4 serve effectually to prevent diagonal expansion of the tread portion of the tube T or that portion of the material of the tube comprised in the depressed portion or inbow 1. It will 25 also be noted that the diagonally disposed ribs 3 and 4 having their intersecting portions integrally connected serve to prevent transverse expansion of that portion of the material comprised in the inbow or de- 30 pressed portion 1 of the tube T.

As is particularly illustrated in Fig. 1 the diagonally disposed ribs or flanges 3 and 4 result in the formation of substantially diamond shaped pockets 5 with the circumferential annular rib 2 disposed centrally of the middle diamonds.

It is also of advantage to have the outer faces of the ribs or flanges 2, 3 and 4 of substantially the same radii as the radius of the 40 circular inner wall of the casing or carcass C. By this arrangement it will be perceived that when the tube T is applied within the casing or carcass C the same will fit snugly therein and the outstanding ribs 2, 3 and 4 45 will not result in the pinching of the inner portion of the tube T.

As is clearly illustrated in Fig. 2 of the accompanying drawings the ribs 2, 3 and 4 maintain the tread portion of the tube T 50 spaced from the inner wall of the tread portion of the casing and carcass C so that the possibility of the tread portion of the tube T being punctured by a member penetrating the carcass C is substantially eliminated. 55 Should a pebble or other comparatively small object pass through the tread portion of the casing or carcass C it will work its way into a pocket 5 and as the tread portion of the tube T will not expand, owing to the 60 arrangement of the ribs 2, 3 and 4, when the tube is inflated, it will be at once self evident that such member within the pocket will not result in a puncture of the tube. It will also be at once appreciated that the 65 ribs 2, 3 and 4 will prevent wear upon the

tread portion of the tire so that the possibility of a blow-out is substantially entirely eliminated. However, in the event that the tread portion of the tube should blow-out the extent of said blow-out will be limited 70 by the flanges 3 and 4 defining a pocket 5 while at the central part of the tread portion said blow-out will be further restricted to the space between adjacent portions of the flanges 2, 3 and 4. 75

It is recognized that when under inflation an expansion of the material comprised in the tube T occurs. This is not prevented in our inner tube as here embodied but such expansion of the material of the tube 80 occurs inwardly of the tread of the tube as defined by the inbow or depressed portion 1.

From the foregoing description, it is thought to be obvious that an inner tube constructed in accordance with our invention 85 is particularly well adapted for use by reason of the convenience and facility with which it may be assembled and operated and it will also be obvious that our invention is susceptible of some change and modification without materially departing from the principle and spirit thereof and for this reason we do not wish to be understood as limiting ourselves to the precise arrangement and formation of the several parts 90 herein shown in carrying out our invention in practice except as hereinafter claimed. 95

We claim:

1. As a new article of manufacture, an inner tube for an inflatable tire provided 100 at its tread with connected protuberances for holding said tread when the tube is inflated in substantially the same state as when the tube is deflated.

2. As a new article of manufacture, an 105 inner tube for a tire having an annularly disposed outstanding continuous rib disposed circumferentially thereof at substantially the transverse center of the tread portion of the tube and circumferentially spaced 110 outstanding ribs carried by the tread portion of the tube and extending transversely thereof.

3. As a new article of manufacture, an inner tube for a tire having an annularly disposed outstanding continuous rib disposed circumferentially thereof at substantially 115 the transverse center of the tread portion of the tube and circumferentially spaced outstanding ribs carried by the tread portion of the tube and extending transversely thereof, said transversely disposed ribs being equi-distantly spaced.

4. As a new article of manufacture, an inner tube for a tire having an annularly 120 disposed outstanding continuous rib disposed circumferentially thereof at substantially the transverse center of the tread portion of the tube and circumferentially spaced outstanding ribs carried by its tread portion 125

130

of the tube and extending diagonally thereof, said diagonal ribs being arranged in two series, the ribs of one series being reversely directed relative to the ribs of the second series.

5. As a new article of manufacture, an inner tube for a tire having an annularly disposed outstanding continuous rib disposed circumferentially thereof at substantially the transverse center of the tread portion of the tube and circumferentially spaced outstanding ribs carried by the tread portion of the tube and extending diagonally thereof, said diagonal ribs being arranged in two series, the ribs of one series being reversely directed relative to the ribs of the second series, the ribs of each series being substantially in parallelism.

6. As a new article of manufacture, an inner tube for a tire having an annularly disposed outstanding continuous rib disposed circumferentially thereof at substantially the transverse center of the tread portion of the tube and circumferentially spaced outstanding ribs carried by the tread portion of the tube and extending diagonally thereof, said diagonal ribs being arranged in two series, the ribs of one series being reversely directed relative to the ribs of the second series, the ribs of one series intersecting the ribs of the second series.

7. As a new article of manufacture, an inner tube for a tire having circumferentially spaced outstanding ribs carried by the tread portion of the tube and extending diagonally thereacross.

8. As a new article of manufacture, an inner tube for a tire having circumferentially spaced outstanding ribs carried by the tread portion of the tube and extending diagonally thereacross, said ribs being arranged in two series, the ribs of one series being reversely directed relative to the ribs of the second series.

- 45 9. As a new article of manufacture, an inner tube for a tire having circumferentially spaced outstanding ribs carried by the

tread portion of the tube and extending diagonally thereacross, said ribs being arranged in two series, the ribs of one series being reversely directed relative to the ribs of the second series, the ribs of one series intersecting the ribs of the second series.

10. As a new article of manufacture, an inner tube for a tire having circumferentially spaced outstanding ribs carried by the tread portion of the tube and extending diagonally thereacross, said ribs being arranged in two series, the ribs of one series being reversely directed relative to the ribs of the second series, the ribs of each series being substantially in parallelism.

11. As a new article of manufacture, an inner tube provided at its tread portion with an annular depression extending circumferentially therearound, and outstanding members arranged within said depression for holding the tread of the tube against expansion, said members being angularly related and extending entirely across the annular depression.

12. As a new article of manufacture, an inner tube for a tire having an annularly disposed outstanding continuous rib disposed circumferentially thereof at substantially the transverse center of the tread portion of the tube and circumferentially spaced outstanding ribs carried by the tread portion of the tube and extending diagonally thereof, said diagonal ribs being arranged in two series, the ribs of one series being reversely directed relative to the ribs of the second series, each rib of one series intersecting a plurality of ribs of the second series.

In testimony whereof we hereunto affix our signatures in the presence of two witnesses.

CECIL H. DUCKETT.
CHARLES J. FITZPATRICK.
